POST LIGHT

Mitchell Bobrick, 605 Erskine Drive,
Pacific Palisades, Calif. 90272

Filed Oct. 3, 1966, Ser. No. 4,140

Term of patent 14 years

(Cl. D48—31)

FIG. 1.

FIG. 2.

FIG. 3.

FIG. 4.

FIG. 1 is a side elevational view of the design for a post light;

FIG. 2 is a top plan view;

FIG. 3 is a bottom plan view; and

FIG. 4 is a fragmentary, side elevational view, with a portion of the shade and lamp broken away and in section.

The broken line showing of a support pole in FIGS. 1 and 3 is for illustrative purposes only.

I claim:

The ornamental design for a post light, as shown and described.
